INFLATION CONTROL FOR UNDERWATER DIVING VESTS

Manfred Schuler, Costa Mesa, Calif., assignor to Pittman Products, Inc., Huntington Park, Calif.

Filed Sept. 13, 1974, Ser. No. 505,790

Term of patent 14 years

Int. Cl. D23—01

U.S. Cl. D83—1 L

FIG. 1.

FIG. 2.

FIG. 3.

FIG. 4.

FIG. 5.

FIG. 6.

FIG. 1 is a front elevational view of an inflation control for underwater diving vests embodying my new design; FIG. 2 is an end view thereof;

FIG. 3 is a rear elevational view thereof;

FIG. 4 is an elevational view taken from the end opposite that shown in FIG. 2;

FIG. 5 is a top plan view; and

FIG. 6 is a bottom plan view.

I claim:

The ornamental design for an inflation control for underwater diving vests, substantially as shown.
